UNITED STATES PATENT OFFICE.

HENRY P. KRAFT, OF RIDGEWOOD, NEW JERSEY.

DESIGN FOR A DUST-CAP FOR VALVES.

49,435.

Specification for Design.

Patented July 25, 1916.

Application filed May 2, 1914. Serial No. 836,030. Term of patent 14 years.

To all whom it may concern:

Be it known that I, HENRY P. KRAFT, a citizen of the United States of America, residing in Ridgewood, in the county of Bergen and State of New Jersey, have invented a new, original, and ornamental Design for Dust-Caps for Valves, of which the following is a specification, reference being had to the accompanying drawing, forming part thereof.

The figure is a perspective view of a dust cap for a valve, showing my new design.

I claim:

The ornamental design for a dust cap for valves, substantially as shown.

In witness whereof, I have hereunto signed my name in the presence of two subscribing witnesses.

HENRY P. KRAFT.
